Primary Examiner—Stella M Reid*Assistant Examiner*—Mark A Goodwin(74) *Attorney, Agent, or Firm*—Armstrong Teasdale, LLP(57) **CLAIM**

The ornamental design for a salad kit, as shown and described.

DESCRIPTION

FIG. 1 is a top perspective view of a salad kit showing my new design;

FIG. 2 is a top plan view thereof;

FIG. 3 is a front view thereof;

FIG. 4 is a right side view thereof;

FIG. 5 is a left side view thereof; and,

FIG. 6 is a bottom plan view thereof.

The broken line showing of the rectangular feature in FIG. 6 is included for the purpose of illustrating environmental structure and forms no part of the claimed design.
